UNITED STATES PATENT OFFICE.

GEORGE W. SUMMERTON AND CLAYTON C. SUMMERTON, OF WABASH, INDIANA.

FLOUR-PRODUCER.

1,244,561.

Specification of Letters Patent. Patented Oct. 30, 1917.

Application filed March 26, 1917. Serial No. 157,340.

To all whom it may concern:

Be it known that we, GEORGE W. SUMMERTON, a subject of the King of England, but who have declared my intention of becoming a citizen of the United States, and CLAYTON C. SUMMERTON, a citizen of the United States, residing at Wabash, in the county of Wabash and State of Indiana, have invented 10 a new and useful Flour-Producer, of which the following is a specification.

It is the object of our invention to provide a machine for producing flour from crushed middlings or other intermediate stock coming directly from the rolls without passing through a bolter or flour dresser, and at the same time to make a better grade 15 of flour than is obtained from rolls, and also to shorten the flour-making process.

The accompanying drawings illustrate 20 our invention. Figure 1 is a vertical longitudinal section through a flour-producer embodying our invention; Fig. 2 is a section on the line 2—2 of Fig. 1; Fig. 3 is a section on the line 3—3 of Fig. 1; Fig. 4 is a perspective view of one rotator and end 25 plate of the rotatable element; and Fig. 5 is a fragmentary longitudinal section through the rotatable element.

A horizontally arranged cylindrical casing 30 8, conveniently of sheet metal, with cast end rings 9 and 10 at the intake and discharge ends respectively, is suitably supported on legs 11, conveniently integral with the end rings, and has removable end plates 35 12 fastened by bolts 13 to internally projecting lugs on the end rings. Such end plates are provided with bearings 14 for the shaft 15 of the rotatable element, which is provided with any suitable driving means, 40 such as a pulley 16. This rotatable element may be removed as an entirety from the casing 10, by being withdrawn endwise, one of the end plates 12 first being removed. In order to prevent longitudinal movement of 45 this rotatable member, it may be provided with collars 17 for bearing against the end plates 12, such collars being adjustably fastened on the shaft 15, as by set screws 18.

The rotatable element on the shaft 15 consists 50 of a number of identical rotators 20, of which one is shown in Fig. 4. Each rotator consists of an annulus 21 connected by a web 22 to a supporting hub 23 adjustably secured on the shaft by a set screw 24, such hub 23 conveniently being on the opposite side of the web 22 from the annulus

21 so that it projects into the space within the annulus of the adjacent rotator, thus facilitating assembling. Projecting downwardly from the annulus 21 are a number of 60 wings 25, which are rearwardly curved somewhat like sections of a spiral, or are convex on their advanced faces, viewed axially. As shown, there are four of these wings on each rotator. The wings 25 at their free ends 65 are convex axially, as is clear from Figs. 1 and 4, and on their advancing faces near their free ends are provided with a plurality of axially extending grooves 26. The rotators may be assembled on the shaft 15 so 70 that the wings 25 of adjacent rotators either are or are not in axial alinement; in the latter case corresponding wings of the different rotators form a helix the pitch of which determines the rate of feeding the 75 stock through the machine, which pitch is adjustable by fastening the different rotators in different circumferential positions on the shaft 15. In order to hold the stock in each rotator for a sufficient time, and prevent it from passing through the machine too rapidly, plates 27 are located between the wings 25 of adjacent rotators, which plates project outward from the annuli 21 80 against the axial ends of the wings 25, and are the full height of the wings 25 on the forward sides of the latter but are of gradually decreasing height as they approach the next wing in advance, as is clear from Fig. 2. Conveniently these plates 27 are formed as 85 webs integral with the annuli 21, as is clear from Figs. 1 and 4. The rotator at the discharge end of the machine (to the right in Fig. 1) has a somewhat similar plate or web 28 (see Figs. 1 and 3) the outer edge of 90 which is circular with the axis of rotation as a center, and which projects nearly or quite to the outer ends of the wings 25, to retard the passage of the stock from this last rotator to the discharge opening somewhat more greatly than it is retarded elsewhere. At the entrance end of the rotator at the intake end of the machine there is a plate 29 carried by its own hub 30 with its set screw 31, which plate 29 is circular 100 and projects outward slightly beyond the surface of the adjacent annulus 21. This is shown in Figs. 1, 4, and 5.

Fixed within the casing 10 and fastened together and to the end rings in any suitable 110 manner, as by dowel pins 35, are a series of rings 37, which fit closely within the casing

10 and the inner surfaces of which are spaced slightly from the outer ends of the wings 25. Conveniently, but not essentially, there are two rings 37 for each rotator, as is clear from Fig. 1, which two rings mate to form an inner surface 38 which is concave in axial cross section, so as to provide a substantially uniform spacing from the convex outer ends of the wings 25. This 10 inner surface 38 is roughened, preferably by being provided with a multiplicity of small bosses 39 arranged in staggered relation in longitudinal rows, against which bosses the stock is thrown in the operation 15 of the machine. The end plates 9 and 10 at the intake and discharge ends (the left and right respectively in Fig. 1) are provided with an intake opening 40 and a discharge opening 41, respectively, which openings lead tangentially into the space within the casing 19, as is clear from Figs. 2 and 3, so that the stock is received into such casing and discharged therefrom tangentially and in the direction of rotation of 20 the rotators. The intake opening 40 and the discharge opening 41 are beyond the first and last rotators, or beyond the plates 29 and 28, respectively, as indicated in Fig. 25 1; though this is not necessary.

30 In operation, the stock to be made into flour is ordinarily first ground or crushed on smooth rolls, and then discharged directly into the intake opening 40 of our flour producer. It is immediately taken up by the wings 25 of the first rotator, and agitated thereby between the wings 25 and the surface 38, passing gradually from one rotator to the next around the edges of the plates 27 until it reaches the discharge end 40 of the machine, where it is discharged through the discharge opening 41. The stock remains in each rotator for some time, before passing to the next, because of the plates 27, and in passing through the machine is reduced to fine granules. When 45 the stock thus discharged from the machine is bolted, it produces a larger percentage of flour than can be obtained from the roller process or any other process known to us, and the flour thus obtained is of better quality, and whiter. The granules of this flour are comparatively sharp grained, and the gluten in the wheat is not affected as in the case of other flour-producing processes. 50

55 Probably this is because the action in our flour producer is a breaking up of the stock by the action for the most part of the particles on one another, the wings 25 and the roughened surfaces 38 merely assisting in the agitation of the stock but producing practically no grinding action themselves on account of the space between the ends of the wings 25 and the surfaces 38. Furthermore, the passage of the stock through the 60 machine is accompanied by a current of air,

which keeps the stock cool and thereby avoids the deteriorating effects of heat. The stock after passing through our machine goes directly to the bolters without any further treatment.

The length of the machine and the number of rotators therein may be varied as desired. The stock may be fed to the machine in some other state than that of middlings, if desired, though we find they produce most desirable results. In some cases, the stock may be passed through the machine more than once, especially if the machine is short, though ordinarily one passage is sufficient.

By our machine, the number of operations required to produce flour is greatly reduced, thereby effecting a great saving of power.

We claim as our invention:

1. A flour producer, comprising a single substantially horizontal cylinder having axially separated inlet and outlet openings, and a rotating element mounted for rotation therein and comprising a plurality of contiguous rotators each of which has an annulus from which a plurality of rearwardly curved wings oblique to the radii and in general parallel to the rotator axis project outward into proximity to the inner surface of said cylinder, the inner surface of said cylinder being provided opposite the wings of the rotator with a plurality of bosses arranged in staggered relation in longitudinal rows.

2. A flour producer, comprising a single substantially horizontal cylinder having axially separated inlet and outlet openings, and a rotating element mounted for rotation therein and comprising a plurality of contiguous rotators each of which has an annulus from which a plurality of wings oblique to the radii and in general parallel to the rotator axis project rearwardly outward into proximity to the inner surface of said cylinder, the inner surface of said cylinder being provided opposite the wings of the rotator with a plurality of bosses arranged in staggered relation in longitudinal rows.

3. A flour producer, comprising a single substantially horizontal cylinder having axially separated inlet and outlet openings, and a rotating element mounted for rotation therein and comprising a plurality of contiguous rotators each of which has an annulus from which a plurality of rearwardly curved wings oblique to the radii and in general parallel to the rotator axis project outward into proximity to the inner surface of said cylinder, said rotating element having outwardly projecting plates between adjacent rotators for retaining the stock in the pockets formed between the wings of the rotators.

4. A flour producer, comprising a single

- substantially horizontal cylinder having axially separated inlet and outlet openings, and a rotating element mounted for rotation therein and comprising a plurality of contiguous rotators each of which has an annulus from which a plurality of wings oblique to the radii and in general parallel to the rotator axis project rearwardly outward into proximity to the inner surface of said cylinder, said rotating element having outwardly projecting plates between adjacent rotators for retaining the stock in the pockets formed between the wings of the rotators. 65
- 13 5. A flour producer, comprising a single substantially horizontal cylinder having axially separated inlet and outlet openings and a rotating element mounted for rotation therein and comprising a plurality of contiguous rotators each of which has an annulus from which a plurality of rearwardly curved wings oblique to the radii and in general parallel to the rotator axis project outward into proximity to the inner surface of said cylinder, the outer ends of said wings being convex axially of the cylinder, and the cylinder being provided with a plurality of axially concave portions opposite the respective rotators. 70
- 18 20 6. A flour producer, comprising a single substantially horizontal cylinder having axially separated inlet and outlet openings, and a rotating element mounted for rotation therein and comprising a plurality of contiguous rotators each of which has an annulus from which a plurality of wings oblique to the radii and in general parallel to the rotator axis project rearwardly outward into proximity to the inner surface of said cylinder, the outer ends of said wings being convex axially of the cylinder, and the cylinder being provided with a plurality of axially concave portions opposite the respective rotators. 75
- 25 28 7. A flour producer, comprising a substantially horizontal cylinder, and a rotating element mounted for rotation therein and comprising a shaft and a plurality of rotators mounted on such shaft, each of said rotators having a hub and an annulus spaced from but connected to the hub and a plurality of wings oblique to the radii and in general parallel to the rotator axis and extending outwardly and rearwardly from the annulus into proximity to the inner surface of said cylinder, said rotators being relatively circumferentially adjustable on said shaft. 80
- 30 35 8. A flour producer, comprising a single substantially horizontal cylinder having axially separated inlet and outlet openings, and a rotating element mounted for rotation therein and comprising a plurality of contiguous rotators each of which has an annulus from which a plurality of wings oblique to the radii and in general parallel to the rotator axis project rearwardly outward into proximity to the inner surface of said cylinder, the outer ends of said wings being convex axially of the cylinder, and the cylinder being provided with a plurality of axially concave portions opposite the respective rotators. 85
- 35 40 9. A flour producer, comprising a single substantially horizontal cylinder having axially separated inlet and outlet openings, and a rotating element mounted for rotation therein and comprising a shaft and a plurality of contiguous rotators mounted on such shaft, each of said rotators having a hub and an annulus spaced from but connected to the hub and a plurality of rearwardly curved wings oblique to the radii and in general parallel to the rotator axis and extending outwardly from the annulus into proximity to the inner surface of said cylinder. 90
- 45 48 10. A flour producer, comprising a single substantially horizontal cylinder having axially separated inlet and outlet openings, and a rotating element mounted for rotation therein and comprising a shaft and a plurality of contiguous rotators mounted on such shaft, each of said rotators having a hub and an annulus spaced from but connected to the hub and a plurality of wings oblique to the radii and in general parallel to the rotator axis and extending outwardly and rearwardly from the annulus into proximity to the inner surface of said cylinder, said rotators being relatively circumferentially adjustable on said shaft. 95
- 50 55 11. A flour producer, comprising an outer casing, a rotatable member comprising a plurality of contiguous sections each of which has a plurality of outwardly projecting rearwardly curved wings oblique to the radii and in general parallel to the rotator axis, the wings of one section being circumferentially spaced from those of the next, and a plurality of rings removably secured within said casing and providing an inner surface having a series of axially concave portions respectively opposite the wings of the different sections of the rotatable member. 100
- 55 60 12. A flour producer, comprising an outer casing, a rotatable member comprising a plurality of contiguous sections each of which has a plurality of outwardly and rearwardly projecting wings oblique to the radii and in general parallel to the rotator axis, the wings of one section being circumferentially spaced from those of the next, and a plurality of rings removably secured within said casing and providing an inner surface having a series of axially concave portions respectively opposite the wings of 105
- 60 65 13. A flour producer, comprising a single substantially horizontal cylinder having axially separated inlet and outlet openings, and a rotating element mounted for rotation therein and comprising a shaft and a plurality of rotators mounted on such shaft, each of said rotators having a hub and an annulus spaced from but connected to the hub and a plurality of wings oblique to the radii and in general parallel to the rotator axis and extending outwardly and rearwardly from the annulus into proximity to the inner surface of said cylinder, the hubs of each rotator being in different planes from the annuli and wings thereof so that the hub of one rotator projects within the annulus of another. 110
- 65 70 14. A flour producer, comprising a single substantially horizontal cylinder having axially separated inlet and outlet openings, and a rotating element mounted for rotation therein and comprising a shaft and a plurality of rotators mounted on such shaft, each of said rotators having a hub and an annulus spaced from but connected to the hub and a plurality of rearwardly curved wings oblique to the radii and in general parallel to the rotator axis and extending outwardly from the annulus into proximity to the inner surface of said cylinder, the hubs of each rotator being in different planes from the annuli and wings thereof so that the hub of one rotator projects within the annulus of another. 115
- 70 75 15. A flour producer, comprising a single substantially horizontal cylinder having axially separated inlet and outlet openings, and a rotating element mounted for rotation therein and comprising a shaft and a plurality of rotators mounted on such shaft, each of said rotators having a hub and an annulus spaced from but connected to the hub and a plurality of wings oblique to the radii and in general parallel to the rotator axis and extending outwardly and rearwardly from the annulus into proximity to the inner surface of said cylinder, the hubs of each rotator being in different planes from the annuli and wings thereof so that the hub of one rotator projects within the annulus of another. 120
- 75 80 16. A flour producer, comprising a single substantially horizontal cylinder having axially separated inlet and outlet openings, and a rotating element mounted for rotation therein and comprising a shaft and a plurality of rotators mounted on such shaft, each of said rotators having a hub and an annulus spaced from but connected to the hub and a plurality of rearwardly curved wings oblique to the radii and in general parallel to the rotator axis and extending outwardly from the annulus into proximity to the inner surface of said cylinder, the hubs of each rotator being in different planes from the annuli and wings thereof so that the hub of one rotator projects within the annulus of another. 125

the different sections of the rotatable member, said axially concave portions being roughened.

13. A flour producer, comprising an outer casing, a rotatable member comprising a plurality of contiguous sections each of which has a plurality of outwardly and rearwardly projecting wings oblique to the radii and in general parallel to the rotator axis, the wings of one section being circumferentially spaced from those of the next, and a plurality of rings removably secured within said casing and providing an inner surface having a series of axially concave portions respectively opposite the wings of the different sections of the rotatable member, the outer ends of said wings being axially convex to correspond with the axially concave portions of the inner surface of said series of rings.

14. A flour producer, comprising an outer casing, a rotatable member comprising a plurality of contiguous sections each of which has a plurality of outwardly and rearwardly projecting wings oblique to the radii and in general parallel to the rotator axis, the wings of one section being circum-

ferentially spaced from those of the next, and a plurality of rings removably secured within said casing in mating pairs, each pair being opposite the wings of one section of said rotatable element and providing an inner surface which is axially concave.

15. A flour producer, comprising an outer casing, a rotatable member comprising a plurality of contiguous sections each of which has a plurality of outwardly and rearwardly projecting wings oblique to the radii and in general parallel to the rotator axis, the wings of one section being circumferentially spaced from those of the next, and a plurality of rings removably secured within said casing and providing an inner surface having a series of axially concave portions respectively opposite the wings of the different sections of the rotatable member.

In witness whereof, we have hereunto set our hands at Wabash, Indiana, this twenty-second day of March, A. D. one thousand nine hundred and seventeen.

GEORGE W. SUMMERTON.
